CORPORATION

MACHINE FOR PRODUCING STAMPED IMPRESSIONS, MARKS, AND THE LIKE

Application filed January 12, 1929, Serial No. 332,083, and in Switzerland January 16, 1928.

This invention relates to a machine for producing stamped impressions or marks of the kind wherein a rotary printing member has in a peripheral aperture a currency or value stamp comprising individually adjustable types representing numbers, and a rotary counting device outside it.

According to the invention a set of cams is provided on the periphery of the said printing member for transmitting at each revolution of the latter the value set thereon to the counting mechanism, which cams are operatively connected each with a setting member for each place value to be set, and at each revolution of the printing member shift, corresponding to the magnitude of the value in question, each a toothed rack arranged to drive a numeral disc of the counter in only one direction, the transference of the tens from one numeral disc to the next being effected separately by means of an auxiliary or second feed device controlled by the printing member.

When the rotary printing member is formed as a hollow cylinder containing rods or bars which extend lengthwise therein and carry numeral types displaceable in their longitudinal and transverse direction, each place value of each of which types can be set in the said aperture of the printing cylinder, according to a feature of the invention the setting members for the types of each place value are slides movable along the said bars, which slides when being moved coact each with a lever which is operatively connected by a transverse slide extending through the wall of the cylinder with one of a plurality of cams arranged adjustably on the periphery of the printing cylinder, so that by shifting the first-mentioned longitudinally movable slides the lift of the cams is varied corresponding to the magnitude of the displacement of the latter slides.

According to another feature of the invention toothed racks serving for rotating the numbered discs of the counters are controlled in such a manner by the printing cylinder by means of levers, that during one revolution of the cylinder they are (a) engaged twice with the counter discs for causing the

latter to be rotated by the said cams on the cylinder and for subsequently transferring the tens by means of other cams of the cylinder, and (b) disengaged twice therefrom for permitting them to return into their initial position. 60

According to a further feature of the invention, the toothed racks have longitudinal slots, in each of which engages one arm of an angle lever actuated by a cam on the printing cylinder, the other arm of which lever so controls a locking device of the allotted counter disc that, when the toothed rack is disengaged, the said disc is held against rotation and, when the rack is engaged, is released.

According to yet another feature of the invention it is arranged that for subsequently transferring the tens from one counter disc to the next, the counter discs are so set at each revolution by a setting pawl or tumbler that is operatively connected with the toothed rack of the next disc, in relation to a lever that is controlled by the printing cylinder and serves to actuate said rack, that the latter is shifted one tooth by the said lever by means of the setting pawl or tumbler, whereby the feed of the following discs takes place in succession.

One embodiment of the invention is diagrammatically illustrated by way of example in the accompanying drawing, wherein :—

Figure 1 is a longitudinal section through a machine according to the invention.

Figure 2 is a plan thereof, with the base and cylinder casing removed in part,

Figure 3 is a section, enlarged, taken on the line III—III in Figure 1,

Figure 4 is a section taken on the line IV—IV in Figure 1,

Figure 5 shows a single numeral disc on an enlarged scale, 90

Figures 6 and 7 are sections taken on the line VI-VI in Figure 1 showing the feed device in two different positions, and

Figures 8 and 9 are sections taken on the line VIII—VIII in Figure 1 showing the counter driving-mechanism in two different positions.

Like reference characters designate like parts throughout the several views. 100

Referring to the drawing, a horizontal hollow printing cylinder 2 is journaled on a base portion 1 of the casing by means of a stub axle 3 in a bearing 4 at one end and an annulus 5 at the other. So many pairs of rods or bars 8 have their rear ends pivoted one beside another on an axle 7 common to them all mounted in the (rear) end wall 6 of the cylinder 2 as the hereinafter described value 10 stamp has place values, namely in the present example five. The pairs of bars 8 extend within the cylinder to its front end where they are carried by bracket 9 having a handle 12 extending through a slot 11 in the front 15 wall of the cylinder 2. Between the bars of each pair of bars 8 is movable a set of ten types 13 for printing numerals. For shifting the entire set of types there extend in front of and behind the same and between 20 the bars 8 of each pair two arms 15 of a setting slider 16, the two arms of a slider being connected together by a pair of bars 14, as shown in Figs. 1 and 3. Each type 13 has a slot 17 into which enters a guide pin 18 25 fast in the pair of bars 14, so that when the pairs of bars 14 are moved upwards the types 13 are driven away from the wall of the cylinder.

At the front end each setting slider 16 carries a setting lever 20 mounted to rock about a horizontal axle 19. The free ends of these levers extend each into a longitudinal slot 21 of the cylinder 2, but normally only so far that they do not project beyond the periphery 30 of the latter. In order to engage the levers 20 and to shift the slides 16 by means of them for setting any one of the types 13 in relation to an aperture 22 in the cylinder 2, the bars 8 must be moved upwards by the handle 12. A 35 presser 23 is movable longitudinally in the middle of the wheel-shaped handle 12 and at its inner end carries a laterally directed arm 24. With the latter there is firmly connected a rod 25 that extends lengthwise in 40 the cylinder 2 and engages under the action of a spring, not shown, in a recess 26, whereof two are arranged one above the other in the end wall. If the presser 23 is driven inwards the rod 25 is disengaged from its recess, whereupon the handle 12 can be set in 45 the upper and then be moved into the lower position. In the upper position of the handle 12 the levers 20 extend so far out of the cylinder 2 that they can be conveniently gripped, 50 as shown in dotted lines in Figure 1. Between the bars of each pair of bars 8 there is opposite the aperture 22 in the cylinder a stop 27 which is firmly connected with the said bars and causes the type 13 under it to enter into 55 the aperture 22 when the handle 12 is moved downwards, so that the outer end of the type in the aperture 22 is flush with the printing face 28 of the cylinder 2. In order that the types 13 can slide readily over the stop 27 60 serving as an abutment for them when the

setting slider 16 is shifted, both the stop and the types are bevelled in front and behind and have slanting faces 27' and 13', respectively.

The types are set exactly in relation to the aperture 22 with the aid of notches 29 formed in the back of each setting slider 16, and a pawl 30 pressed downwards by a spring 31 on to the slider 16 or into a notch 29 therein. All the pawls 30 are pivoted on an axle 33 that is common to them all and has its ends held in side plates 32. Levers 34 are pivoted beside the pawls 30 on the axle 33 and have each a lateral pin 35 engaging in a slanting slot 36 in an allotted setting slider 16. When the latter is shifted endwise the allotted lever 34 is moved upwards more or less, corresponding to the distance the slider is displaced out of its normal position shown in full lines in Figure 1.

Each lever 34 has a forked end engaging a finger of a transverse slide 38. The five slides 38 are guided to move close together in a guide 39 that extends through the wall of the cylinder 2. Each slide 38 is connected by an outwardly extending arm 38' with a transverse cam 40 which has its one end forked and is guided to move transversely of the cylinder 2 on a rod 41 which extends lengthwise of the cylinder and is attached thereto. The five 95 cams 40 are equally spaced apart at the cylinder 2 in the direction of its length. In the path of each cam 40 below the cylinder and lying transversely of the latter is a lever 42; these levers are pivoted on an axle 43 that is 100 common to them all and are pressed upwards each by a spring 44.

To ensure that all the levers 42 shall lie in their upper end position at exactly the same height, a bar 45 reciprocated up and down by a bell crank 46 is arranged below them. For actuating this lever 46 it is firmly connected with a lever 47 carrying an antifriction roller 48 that bears under spring pressure on the periphery of a cam 49 fast on the cylinder 2. Each lever 42 carries within reach of the allotted cam 40 an antifriction roller 50 and engages at its free end by means of a lateral pin 51 in a slot 52 of a vertical toothed rack 53.

Owing to the vertical reciprocation of the lever 42 the racks 53 are moved up and down, in each case a shorter or longer distance according to the position of the allotted cam 40. Only the downward movement of the toothed racks out of their upper end position is transmitted to two pinions 54 and 55, two for each rack, which pinions are connected each with a numeral disc 56 and 57 respectively of two counting devices arranged one above the other. The upper of these counters serves for rendering visible the total sum recorded, whilst the lower counter serves for printing this total on a check strip, not shown, and for this purpose has types on the periph- 130

ery of its discs. If a double control is not required one of the two counters may be omitted.

In order that the upward movement of the 5 toothed racks 53 shall be inoperative on the counters, the racks are disengaged in the lower end position each by a cam 58 by means of a lever 59, said cam 58 being arranged on the periphery of the cylinder 2. Each lever 10 59 engages in a recess in a double link 61 which couples together two three-armed levers 62 and 63. These levers are freely rotatable each on an axle 64 and 65 respectively, which axles enter into slots 66 in the 15 toothed racks 53. The upwardly directed arms of the levers 62 and 63 carry anti-friction rollers 67 situated each in the slot 66 of the allotted toothed rack. A third arm of each of the levers 62 and 63, which are arranged 20 one above the other, engages between the numbered discs of the counters and has an upwardly directed stop or tooth 68 which, when the toothed rack is disengaged, as shown in Figure 9, engages in a locking ring 69 of 25 the teeth fast on the allotted numbered disc and thereby locks the latter against rotation. When the link 61 moves upwards the levers 62 and 63 are rocked so that their upstanding arms throw the racks into engagement with 30 their pinions, whilst their arms carrying the teeth 68 release the numeral discs. Reverse- 35 ly, when the link 61 moves downwards the toothed racks are disengaged from their pinions by the levers 62 and 63 and the numbered discs are locked.

In consequence of the individual drive of the first five numeral discs of each counter, corresponding to the highest number of place values present in the printing cylinder, the 40 tens must be transferred from four numeral discs, i. e. from the units disc to the tens disc, from this to the hundreds, from this to the thousands disc and from this to the ten-thousands disc with the aid of a second or auxiliary feed device described hereinafter. The 45 tens are transferred by the other discs each to the next disc in the manner customary in counting mechanism by means of intermediate toothed wheels. The said second or auxiliary feed device comprises above the toothed rack for driving the tens discs, herein referred to briefly as the "tens rack", as well as above the hundreds, thousands and ten-thousands rack, a tumbler or detent 50 which is pivoted at 71 on a lever 73 fulcrumed at 72, and is held by a spring 74 against a stop 75. The lower end of each lever 73 lies in the range of a cam 76 of the numbered disc of the next lower place value and, at each 55 revolution of this disc or cam, is so rocked that an upwardly directed tooth 70' of the tumbler 70 arrives in front of a downwardly directed tooth 77' of a lever 77 extending over the said tumbler. The four levers 77 are 60 mounted on an axle 78 common to them all

and are connected each by a bail or stirrup 79 to one end of a lever 80. The other end of each lever 80 carries an anti-friction roller 81 which bears against a cam 82 of the cylinder 2 and is so controlled by the latter that the allotted lever 77 is moved a distance up and down which suffices, after the lever 77 has struck the tooth 70' of the tumbler 70 under it, to move downwards by means of the latter the allotted toothed rack a distance equal to 75 one tooth, i. e. one unit of the allotted numeral disc, and to feed the latter one number.

In order that the transference of the tens shall take place always in the correct order, i. e. from a lower place value to the numeral disc of the higher place value, the four cams 82 are staggered one relatively to another an amount such that the lever 77 of the next higher place value is actuated only after the lever of the next lower place value has been 80 moved downwards. As the second or auxiliary feed device for the transference of tens must be actuated subsequently to the ordinary feed of the numbered discs by the cams 40, and always from the same starting or initial 85 position of the toothed racks 53, the latter are disengaged after each ordinary feed movement, moved into the upper end position and engaged again with the pinions 54 and 55 of the numbered discs at each revolution 90 of the printing cylinder. A toothed rack is then moved down however, only when the tumbler 70 over it has been brought by the lever 73 in question into the range of the allotted lever 77. Otherwise, the latter can 95 rock freely downwards without striking the tumbler 70 and without effecting a supplementary feed of the numeral discs in question.

A hollow table 83 is provided for bearing 100 the letter or the like to be printed, for example impressed with a currency value for franking it, which letter or the like is fed by a roller, not shown, at a suitable moment to the printing cylinder from below the latter.

The described machine is manipulated and 105 operates, briefly, as follows:—

In a predetermined position of the printing cylinder 2 and when the bars 8 are set in their upper position, the types 13 for effecting the printing are set at the aperture 22 of the cylinder by means of the levers 20 extending out of the latter and, when the bars 8 are moved downwards, are moved into the said aperture, i. e. into the printing position. When the types are being set in the printing position the cams 40 are set, by means of the levers 34 and slides 38, in a position relatively to the cylinder corresponding to the set numeral of the place value in question, so that each projects 115 more or less beyond the cylinder. When the cylinder is then turned by hand or by a motor, the types and, if desired, a mark-cliché surrounding the same, are provided with ink by an inking device, not shown, and caused 120

to print a letter or the like lying on the table 83. During the rotation of the printing cylinder the cams 40 coat with the levers 42 and move these downwards, each according to the position of the allotted cam, against the action of the springs 44. The toothed racks 53 have previously been engaged with the pinions 54 and 55 by the lever mechanism 59, 61, 62, 63 and are moved downwards more or less by the levers 42, and they rotate the said pinions and counter discs a corresponding angular distance. If during this rotation a numbered disc passes its zero position its cam 76 rocks its lever 73 and places the tooth 70' of the tumbler 70 under the allotted lever 77, whose tooth 77' prevents the tumbler from returning into its normal position. As soon as the toothed racks 53 have arrived into their lower position they are disengaged by the cam 58 from the pinions 54 and 55, whereupon they are moved under the influence of the springs 44 into the upper position limited by the tumblers 70. The auxiliary or second feed device for transferring the tens then operates, beginning with the tens rack and ending with the ten-thousands rack. Only that toothed rack is moved downwards one tooth, however, whose allotted tumbler 70 for transmitting the downward movement of the allotted lever 77 is set on the rack. All the other toothed racks remain in their upper end positions. After this second feed movement and the stamping of the letter or the like have taken place, the machine is ready for producing a new stamp, mark, impression or the like, and the described cycle of operations is then repeated.

I claim:

1. In a machine of the character described, the combination of a hollow rotary printing member having an aperture in its periphery, a plurality of numeral printing types therein, a rotary counting device outside the printing member comprising numbered discs, a plurality of toothed racks allotted each to a said disc for rotating the same, a plurality of setting members, one for each place value of the counting device, for selectively setting the types individually in printing position in said aperture, a plurality of cams on the periphery of said printing member, one cam allotted to and operatively connected to each setting member so as to be adjusted thereby corresponding to the value of the types at the aperture, means arranged to be actuated at each revolution of the printing member by said cams and shift said racks so as to rotate the allotted discs in only one direction, and tens transfer mechanism controlled by said printing member and arranged to transfer the tens from one disc to the next.

2. In a machine of the character described, the combination of a hollow rotary printing cylinder having an aperture in its periphery, a plurality of bars extending lengthwise

therein, a plurality of numeral types movable along and transversely of said bars, a rotary counting device outside said cylinder comprising a plurality of numbered discs allotted each to a set of types of a predetermined place value, a plurality of sliders movable along said bars, one for each place value, for selectively setting the types individually in printing position in said aperture, a plurality of cams on the periphery of said printing cylinder, a plurality of transverse slides that extend through the wall of the cylinder and are connected each to one of said cams and arranged to vary the lift thereof, a plurality of levers each operatively connected to a slider and a transverse slide for adjusting the cams corresponding to the magnitude of displacement of the sliders, a plurality of racks allotted each to a disc of the counting device, actuating means arranged to be actuated at each revolution of said cylinder by said cams and shift said racks so as to rotate the allotted discs in only one direction, and tens transfer mechanism controlled by said cylinder and arranged to transfer the tens from one disc to the next.

3. In a machine of the character described, the combination of a hollow rotary printing cylinder having an aperture in its periphery, a plurality of numeral printing types movable therein, a rotary counting device outside the cylinder comprising numbered discs, a plurality of toothed racks allotted each to one of said discs for rotating the same, a plurality of setting members, one for each place value of the counting device, for selectively setting the types individually in printing position in said aperture, a plurality of cams on the periphery of said cylinder, one cam allotted to and operatively connected to each setting member so as to be adjusted thereby corresponding to the value of the types at the aperture, means comprising levers, allotted one to each cam and its allotted rack, arranged to be actuated at each revolution of said cylinder by said cams and shifting said racks so as to rotate the discs in only one direction, a second plurality of cams on the periphery of said cylinder, tens transfer mechanism controlled by the said second plurality of cams arranged to transfer the tens from one disc to another, and means controlled by the rotation of the cylinder for disengaging the racks from their allotted discs twice each revolution of the cylinder to permit them to return to their initial position.

4. In a machine of the character described, the combination of a hollow rotary printing cylinder having an aperture in its periphery, a plurality of numeral printing types movable therein, a rotary counting device outside the cylinder comprising numbered discs, a plurality of longitudinally slotted toothed racks allotted one to each of said discs for rotating the same, a plurality of setting mem-

bers, allotted one to each of said discs, for selectively setting the types individually in printing position in said aperture, a set of cams on the periphery of said cylinder, which 5 cams are allotted each to and operatively to a setting member so as to be adjusted thereby corresponding to the types at the aperture, means arranged to be actuated at each revolution of the cylinder by said cams and reciprocate said racks and thereby rotate the 10 allotted discs in only one direction by endwise movement of the racks in one direction, means comprising angle levers, each having an arm engaging in a slot in one of said racks, for disengaging the latter from the discs 15 when the racks move endwise in the other direction, which angle levers serve each to lock the allotted disc when the racks are moving endwise in the latter direction and are 20 disengaged from the discs, and tens transfer mechanism controlled by said cylinder and arranged to transfer the tens from one disc to the next.

5. A machine as set forth in claim 1, where-
25 in the tens transfer mechanism comprises a plurality of levers one less in number than the number of racks and allotted each to one of the racks except that allotted to the disc of lowest place value, a plurality of tumblers 30 allotted one to each lever and arranged operatively to connect the latter with the allotted rack, and means for controlling each tumbler by a disc of next lower place value than that corresponding to the rack to which the tumbler 35 is allotted and thereby making and breaking the operative connection of said levers with the racks, which levers are arranged to be rocked by cams on the cylinder and thereby shift the racks endwise to rotate 40 the discs when the tumblers are operative between the levers and the racks.

6. In a calculating machine, a setting up mechanism comprising a plurality of bars, a plurality of numbered types slidably longitudinally and transversely of adjacent sets 45 of said bars, means on which each of said sets of types are mounted, the individual types being slidable transversely of their respective means, a fixed cam member for forcing a 50 selected one of each set of types into operable position, projecting levers for actuating each of said means, said levers being normally retracted, and means for forcing said levers into their projected position wherein they 55 can be operated to set the said means.

In testimony whereof I affix my signature.
ULRICH KOHLER.
